J. PFEIFER

PERMUTATION LOCK

Filed Dec. 5, 1921

UNITED STATES PATENT OFFICE.

JOHN PFEIFER, OF SPRINGFIELD, OHIO, ASSIGNOR TO THE SPRINGFIELD AUTO LOCK COMPANY, OF SPRINGFIELD, OHIO, A CORPORATION OF OHIO.

PERMUTATION LOCK.

Application filed December 5, 1921. Serial No. 520,098.

To all whom it may concern:

Be it known that I, JOHN PFEIFER, a citizen of the United States, residing at Springfield, in the county of Clark and State of Ohio, have invented certain new and useful Improvements in Permutation Locks, of which the following is a specification.

My invention relates to permutation locks, 10 it particularly relating to improvements upon the locking device described in my pending application No. 397,938 filed July 21, 1920.

An object of my invention is to provide 15 means for preventing unauthorized unlocking of the mechanism by persons without knowledge of the proper combination.

A further object of my invention is to provide a mechanism of the character referred to which will be simple in its construction and effective for the purpose for which it is designed.

In the accompanying drawings:—

Fig. 1 is a front elevation of a lock embodying the improvements, showing the parts in locking position.

Fig. 2 is a similar view showing the parts in unlocked position.

Fig. 3 is a top plan view of one of the locking elements.

Fig. 4 is a vertical sectional view of several of the locking elements in assembled position.

Fig. 5 is an elevation of the locking bolt and devices carried thereby which cooperate with the locking elements to insure the unauthorized unlocking of the bolt, these devices being shown in their inoperative position.

Fig. 6 is a section on the line 6—6 of Fig. 5, showing the devices carried thereby in their operative position.

Fig. 7 is a partial section showing the devices carried thereby in their inoperative position or in the same position in which they are shown in Fig. 5.

Fig. 8 is a vertical section through the entire mechanism showing the parts in locking position.

Fig. 9 is a perspective view of a portion of the devices carried on the bolt.

Fig. 10 is a view of the lower end of the bolt.

The lock herein described is one which 55 has been particularly devised for the pur-

pose of locking certain parts of an automobile such as the steering wheel or the gear shifting lever, the particular manner of applying the lock for the purpose of locking the steering wheel being described in my pending application referred to and another installation of the lock for the purpose of locking the shifting lever being described in an application filed Dec. 5, 1921, Ser. No. 520,099. The locking mechanism is carried by two supporting brackets or ears 1 and 2, which are a part of any suitable form of supporting member which will enable the mechanism to be applied to the part to be locked. A locking bolt 3 is slidably mounted in aligned apertures 1^a and 2^a in said ears with the locking devices therefor assembled about the bolt between the ears. These locking devices consist of a series of outer sleeves 4, three in number in the present case, each provided with an inner ring 5. Each sleeve has equally spaced indications from 0 to 9 and between each indication is a vertical groove 6, which cooperates with spring fingers (not shown in the present case) to hold the sleeves in their adjusted positions and to act as clickers. Each sleeve has an integrally formed inner flange 7 at its lower end upon which its rings rests and projecting up from each of these flanges is a pin 8 which may be received in any one of a series of outer vertically-arranged notches 9 in its corresponding ring to provide means for changing the combination. In the two upper sleeves this flange projects below the lower edge thereof as shown in Figs. 4 and 8, so as to telescope with the adjacent sleeve. Each of the rings 5 is fitted to the interior of its corresponding sleeve 4 resting upon the flange 7 and in the upper sleeve the ring is of a length equal to the distance between the upper end of the sleeve and its flange but in the intermediate and lower sleeves the ring is shorter so as to accommodate the flange of the sleeve immediately above it. When the rings are assembled in the sleeves, a small indication 10 as shown in Fig. 3 is caused to register with that indication upon the sleeve which represents the number of the desired combination. For instance, the combination at which the mechanism is set in the drawings is 000 so that this mark 10 in each of the rings will be placed opposite the indications "0" of the 110

sleeves. The pin 8, therefore, locks the inner rings in fixed relation with the respective sleeves so far as revoluble movement is concerned.

5 Each ring 5 has diametrically opposite the indication 10 a vertically extending interior slot 11. The extreme upper portion of the upper ring is formed with an enlarged bore as indicated at 5^a so that the 10 upper edge thereof may stand flush with the upper edge of its sleeve, so that when the sleeves and rings are in an assembled position between the ears, they will be held against any vertical displacement; this 15 construction leaving the grooved portion of said upper ring of the same size as that of the other two rings for a purpose to be explained.

The locking bolt 3 is provided with a 20 series of aligned projections 12, in the present case four in number, and also at the upper and lower ends with ribs 13 and 14 in alignment with the projections. Each of the ears has a vertical slot 15 and 16 in the 25 wall of the aperture therethrough, these slots being aligned. The distance between the ribs and adjacent projections and also between the projections is slightly greater than the width of the intermediate and 30 lower rings and of the grooved portion of the upper ring. When the parts are in assembled position and the grooves 11 of the respective rings in alignment with each other, and also with the ribs and projections 35 of the bolt, the bolt may be moved to or from locking position. To lock the bolt the sleeves and their rings are turned to bring the grooves 11 of the rings out of the path of the projections on the bolt and to 40 unlock the bolt it is then necessary to turn the sleeves back to that point which again aligns the grooves in the rings with each other and with the projections and ribs, the points to which these sleeves are turned being determined by the combination. The 45 bolt has at each end a stop 17 and 18, one of which 17 is removable, and when the bolt is in its extreme upper or lower position as determined by these stops, the intermediate and lower rings and the grooved portion of the upper ring will be in alignment with the space between the projections and ribs of the bolts, so that the sleeves and 50 their rings can be turned about the bolt for the purpose of unlocking or locking same.

While the construction shown in my pending application referred to has much merit and is ordinarily effective for the purpose for which it is designed, yet it has developed that some persons expert in locking mechanism of this character have been able to unlock the mechanism of that application by manipulating the bolt in such a fashion as to locate the grooves in the rings 55 for the reason that the bolt necessarily has

more or less inherent play through the rings and ears and when moved up and down the projections on the bolt come in contact with the upper and lower ends of the rings, thus enabling the slots 11 to be located by 70 persons having an uncommonly fine sense of touch. It was to prevent such manipulation of the mechanism that the so called "fooler notches" were placed in the rings in the pending application referred to and 75 while, as before stated, these were effective, yet it has been found desirable to eliminate practically all danger of the lock being so manipulated by persons expert in such mechanism, to accomplish which I have devised the following arrangement:

The bolt 3 has a longitudinally extending channel 19 and rotatably mounted in this channel is a shaft 20 cut away to form two eccentric pins 21 and a central flattened face 20^b; the shaft being held in the channel by a curved retaining finger 20^a. Extending from points in line with the projections on the bolt to points which communicate with the channel is a series of apertures 22 which receive a series of pins 23 projecting from a frame bar 24, each end of which has a hook-shaped projection 25 which embraces the eccentric pins 21. As the shaft is rocked in one direction, which it may be by the 90 pin 26, on the lower end thereof, the face 20^b, coming in contact with the edge of the bar 24, projects the pins 23 from the apertures, and when the shaft is rocked in the opposite direction, the eccentric pins, 95 through the projections 25, withdraws the pins 23, for the purpose to be explained. Projecting from the shaft is a pin 27 which when rotated to the position shown in Fig. 5, lies in a recess 28 of the bolt so as to clear 100 the lower ear 2 as the bolt is moved to or from locking position. When the bolt has been pushed to complete locking position, as shown in Fig. 8, rotation of the shaft 20 projects the pin 27 to a position to bring 105 the ear 2 in its path, the pin being so positioned on the bolt that any play of the bolt downwardly after it has been locked will be limited by the pin; while any loose play of the bolt in an upward direction is 110 limited by the stop pin 18. The pins thus serve to limit the loose play of the bolt to an extent which will prevent any of the projections of the bolt from coming in contact with the interlocking rings and thereby 115 prevent any such manipulation of the bolt as would enable a person to locate the grooves in these rings.

After the locking bolt has been pushed to its locking position, before the sleeves 4 can 125 be rotated to destroy the combination and lock the bolt, it is necessary to rock the shaft 20 to bring the pin 27 in proper operative relation with the ear 2 for the reason that the small pins 23 act as a bar against 130

rotation of the sleeves as shown in Fig. 6, until the shaft has been rocked to withdraw the pins to the position shown in Fig. 7. The sleeves now having been turned to lock the mechanism, it will be impossible to again rock the shaft for the reason that any attempt to do so will be resisted by the pins 23 coming in contact with inner walls of the rings 5 so that it will therefore be necessary to first unlock the mechanism by rotating the sleeves back to the proper combination before the shaft can be rocked to place the pin 27 in the recess 28. In order that there will be no danger of a person expert in such matters being able to locate the grooves 11 of the rings by manipulating the shaft 20 and thereby feeling for those grooves with the fingers 23, I have placed in each of the rings 5 a series of vertically extending shallow grooves 29, unequally spaced, which grooves will permit a slight rotation of the shaft 20 limited by the contact of the ends of the fingers 23 with the walls of the shallow grooves 29, or with the division walls between the same. In this connection it should be explained that the flat face 20^b of the shaft 20, coming in contact with the edge of the bar 24 at an angle thereto, for the purpose of pressing the bar 20 and its pins 23 to the position just referred to, will not have the effect of causing the ends of the fingers 23 to make contact with the walls of the rings 5 with any considerable force, as would be the case if a more direct pressure was placed upon the bar 24, with the result that there will be no such amount of frictional engagement between the ends of the fingers 23 and the rings as would enable a person, by slightly rotating the rings within the limits allowed, to detect whether or not the pins were making contact with the walls of the rings or were coinciding with the deep grooves 11.

The operation of the devices is as follows:—

With the parts shown in unlocking position as indicated in Fig. 2, with the pin 27 lying in the recess 28, the bolt may be pushed to the locking position shown in Fig. 1 and the shaft 20 then rocked to the left so as to move the pin 27 to the position indicated in Fig. 8, in which position the pin acts as a stop against downward movement of the bolt by coming in contact with the upper side of the ear 2. Any upward movement of the bolt is limited by the contact of the pin 18 with the lower side of the ear. These pins 18 and 27 are so positioned that very little loose play of the bolt will be permitted, and whatever loose play there is will not be sufficient to allow the projections 12 to come into contact with the rings 5 so that it will be impossible to locate the grooves 11 by this method. When the locking bolt is pushed to locking position, the pins 23 will

be positioned as shown in Fig. 6, but as they are aligned with the projections 12 they will be permitted to pass freely through the grooves 11. When the shaft 20, however, is rocked to the position shown in Figs. 1 and 8, these pins 23 are withdrawn to the position shown in Fig. 7. The sleeves 4 now having been turned to lock the bolt it will be seen that any attempt to rock the shaft 20 to the right will be resisted by the pins 23 coming into contact with the walls of the shallow grooves 29 in the respective rings 5, or with the division walls between the grooves, thus making it impossible to detect the location of the deep grooves 11 by the aid of these fingers 23, or by reason of the unequal spacing of the shallow grooves, making it further impossible to detect whether the combination has been set on even numbers or half numbers; it being understood in this connection that there are provided twenty of the notches 9 in each ring so that the combinations may be set on half numbers if desired. To unlock the mechanism the sleeves are rotated to the proper combination, the shaft 20 rocked to the right to bring the ear 2 out of the path of the pin 27, and the bolt then slid downwardly to unlocking position.

Having thus described my invention, I claim:—

1. In a permutation locking mechanism, a non-rotatable locking member movable in the direction of its length, locking devices for said member, said member having more or less inherent loose motion, when locked, with relation to said locking devices, and means for confining the loose play of said locking member, when in its locked position, within limits which will prevent the locking devices from being contacted thereby, for the purpose specified.

2. In a permutation locking mechanism, a non-rotatable bolt, locking devices for said bolt, said bolt being movable relatively to said devices and when locked thereby and having more or less inherent loose play in the direction of its length with respect thereto, and means for confining the loose play of said bolt within limits which will prevent the locking devices from being contacted thereby, for the purpose specified.

3. In a permutation locking mechanism, a non-rotatable slidable bolt having projections, locking devices rotatable about said bolt and having grooves to permit the passage therethrough of said projections, said bolt having more or less inherent loose play in the direction of its length when locked by said devices, and means for confining the play of said bolt within limits which will prevent the projections from making contact with said grooved locking devices.

4. In a permutation locking mechanism, a non-rotatable slidable bolt having project-

tions and having more or less inherent loose play in the direction of its length when in locked position, locking devices rotatable about said bolt and having grooves to permit the passage therethrough of said projections, a stop on said bolt to limit its play in one direction, and a second movable stop on said bolt to limit its play in the opposite direction when in locked position, 10 said second stop being locked by said locking devices in the locked condition of the mechanism.

5. In a permutation locking mechanism, a non-rotatable slidable bolt having projections and having more or less inherent loose play in the direction of its length when in locked position, locking devices rotatable about said bolt and having grooves to permit the passage therethrough of said projections to unlock the bolt, means for limiting the movement of said bolt toward locking position, and means to limit the free play of said bolt from locking position, said last-mentioned means being capable of being placed in operative position after the bolt has been placed in locking position and being entirely independent of said locking devices.

6. In a permutation locking mechanism, 30 a non-rotatable lengthwise movable bolt, locking devices for said bolt, said bolt having an inherent loose play in the direction of its length with relation to said locking devices when in locked position, a stationary part through which said bolt slides, and stops carried by said bolt cooperating with said stationary part to limit the loose play thereof, one of said stops being movable to operative position after said bolt has 40 been placed in locking position.

7. In a permutation locking mechanism, a lengthwise movable bolt, locking devices for said bolt, said bolt having an inherent loose play in the direction of its length with 45 relation to said locking devices when in locked position, a stationary part through which said bolt slides, and stops carried by said bolt cooperating with said stationary part to limit the loose play thereof, one of said stops being movable to operative position after said bolt has been placed in locking position, and means whereby said movable stop is locked in its operative position by said locking devices when said devices 55 are moved to locking position.

8. In a permutation locking mechanism, a lengthwise movable locking bolt, locking devices for said bolt comprising a rotatable ring having a groove, a stop on said bolt 60 to limit its movement from locking position, and locking devices for said stop cooperating with the inner wall of said ring to lock the stop in its operative position and cooperating with the groove in said ring to 65 permit unlocking of the stop.

9. In a permutation locking mechanism, a lengthwise movable locking bolt, locking devices for said bolt comprising a rotatable ring having a groove, a stop on said bolt to limit its movement from locking position, and locking devices for said stop cooperating with the inner wall of said ring to lock the stop in its operative position and cooperating with the groove in said ring to permit unlocking of the stop, the 70 inner wall of said ring having a plurality of recesses of lesser depth than said groove. 75

10. In a permutation locking mechanism, a bolt having projections, locking devices for said bolt having grooves to permit the 80 passage of said projections, a stationary part through which said bolt is movable, said bolt having more or less inherent loose play, a stop carried by said bolt to cooperate with said stationary part to limit the loose 85 play of said bolt, in one direction, together with means for limiting its play in the opposite direction, fingers movable with the stop and cooperating with the locking devices to lock said stop in its operative position and cooperating with the grooves to permit said stop to be thrown to inoperative position.

11. In a permutation locking mechanism, 90 a bolt, rotatable locking devices surrounding said bolt and having grooves, projections on said bolt capable of passing through said grooves when aligned to permit said bolt to be moved to and from locking position, and being locked by said devices when said 100 grooves are thrown out of alignment, said bolt having more or less inherent loose play through said locking devices when in locked position, a shaft carried by said bolt, a projection on said shaft, a fixed part through 105 which said bolt projects, said projection when said shaft is rocked cooperating with said fixed part to limit the loose play of said bolt in one direction, one or more fingers slidably mounted in said bolt and operatively connected with said shaft and cooperating with the walls of said locking devices to prevent said shaft from being rotated to bring said projection out of cooperative relation with said fixed part until 115 said grooves have been aligned.

12. In a permutation locking mechanism, 120 a movable locking member, locking devices for said member including rotatable parts, said member having more or less inherent loose motion with relation to said locking devices, means for confining the loose play of said locking devices including a rotatable shaft having an inclined face, a bar 125 cooperating with said inclined face, and pins on said bar cooperating with said rotatable parts to retain said shaft.

In testimony whereof, I have hereunto set my hand this 17th day of November 1921.

JOHN PFEIFER.
